CONTAINERS

Bertram W. Colman, Jr., Kenilworth, Ill., assignor to Republic Molding Corporation, Chicago, Ill., a corporation of Illinois

Application July 27, 1953, Serial No. 370,421

4 Claims. (Cl. 150—0.5)

The present invention relates to containers for the storage of food and the like and closures for such containers, and has particular reference to a structure wherein the closure engages the container hermetically to seal the same and yet permit quick removal and replacing of the closure without damage either to the container and enclosure or to the contents in the container.

In the plastic container art where either the container or the cover, or both, are made of a relatively flexible type of plastic material, like polyethylene for example, it is a difficult problem to provide a satisfactory seal between the larger sizes of containers and covers. Unlike smaller containers such as bottles, etc., where the opening for the closure is small, the area to be covered by the closure means of larger containers will not readily admit of a structure that will lend support for and hold the cover in place. In certain instances, frictionally fitting covers have been used, but the difficulty with them has been to obtain the proper fit in order to maintain a tight seal. In many instances, the covers will tend to displace themselves while the containers are in use. This is particularly true if the containers are used in low temperatures.

An object of the invention is to provide a new and improved form of container and closure means therefor which may be used on larger sizes of containers and which will not only provide a hermetical seal at all times, but assures the retention of the closure means in position.

A further object of the invention is to provide a new and improved container and closure means of this type which includes a positive locking action between the container and closure means that holds the cover tightly in position and preferably requires flexing of either the cover or the container, or both, to free the cover.

A still further object of the invention is to provide a new and improved container and closure means of this type which is simple, efficient and easy to handle. Although the cover will hold itself with considerable tenacity upon the container and maintain the hermetical seal, it may be easily removed, and without the use of tools, by a mere distortion of the flexible part, whether the container, cover or both. The parts are purposely designed to permit this flexing to free the positive locking action when the flexing is performed in a manner which normally does not occur in the handling or use of the container. Accidental displacement of the cover from the container will therefore not readily occur.

In one form of the invention a container is provided with a groove or the like on its inside face at a predetermined distance from its outer edge. The cover is provided with a flange having a laterally projecting rib spaced at a distance on the flange so that when the cover is in position on the container, the flange brings the rib into engagement in the groove by a definite mechanical interlock, the rib having a greater outer dimension than the inner dimension of the container whereby when the rib is forced into the groove the cover cannot be removed. A hermetical seal may be obtained by providing abutting

2

surfaces or faces on the container and cover that cause the rib to lie tightly against the upper face of the groove in the container.

In order to apprise those skilled in the art how to construct and practice my invention, I shall now describe a preferred embodiment of the same taken in connection with the accompanying drawings which form a part thereof.

In the drawings:

10 Figure 1 is a perspective view of one form of container and closure means of considerable diameter embodying the present invention;

15 Fig. 2 is a transverse section through the same and illustrating the cover in detached position;

15 Fig. 3 is an enlarged sectional view illustrating the positive locking means employed;

Fig. 4 is a perspective view showing one way of removing the cover from the container;

20 Fig. 5 is a top plan view with a portion of the cover broken away to illustrate a different shape and type of container embodying the invention;

Fig. 6 is an enlarged perspective view of one end of this container to show a way of removing the cover therefrom;

25 Fig. 7 is an end view of the container and cover shown in Fig. 5, but with a portion broken away and the remaining portion shown in section; and

Fig. 8 is a partial detail view in elevation and in section to illustrate how the cover fits upon the container body.

30 The container illustrated in Figs. 1 to 4, inclusive, comprises a circular body 5 provided with a side wall 6 and a base 7. The material may be any suitable plastic, or it may be a flexible material that will yield slightly when pressure is applied to side wall 6. Closure means in the

35 form of cover 8 may also be of a suitable plastic or a flexible material that will yield slightly when pressure is applied thereto. It will be apparent from the structure disclosed that either body 5 or cover 8 may be of relatively rigid material if the other member is of a flexible

40 character, the purpose being to flex at least one of these parts to permit the cover to be seated and provide and maintain a vapor-tight seal or to permit the cover to be removed.

45 This structure preferably comprises a downwardly or inwardly projecting flange 9 extending from the under face of cover 8 and a rib 10 extending from this flange 9. A groove 11 is formed about the inside face 12 of body 5 to receive rib 10. It will be observed that it is desirable to provide distance *a* marked in Fig. 2 on body 5 about equal to the distance *b* on the cover 8, this distance *a* representing the depth or distance of wall 13 extending from top edge 14 down to the corner edge 15 of the upper face 16 of groove 11. Distance *b* represents the depth or distance of the upper face 17 of rib 10 to the under face 18 of the edge flange 19 of cover 8. Thus, when rib 10 is seated in groove 11, face 18 of cover edge flange 19 is pulled tightly against the upper surface 20 of wall 6 and a vapor-tight seal is formed between body 5 and cover 8.

50 It will be observed in Fig. 3 that the thickness or depth represented at 21 of rib 10 need not be the depth of groove 11, it being desirable in this connection that rib 10 should fit tightly against the upper face of this groove to obtain this vapor-tight seal and hold the cover in place.

55 Cover 8 extends beyond wall 6 of body 5. It is this extension in the design of the container shown in Fig. 1 that forms cover flange 19. This cover flange 19 bears against upper face 20 of wall 6. It is this tight-fitting action of rib 10 against upper face 16 and cover flange 19 against upper face 20 that holds the cover tightly in position and assures a vapor-tight hermetical seal.

60 To withdraw rib 10 from groove 11, one of two oper-

ations should take place. Either the body 5 should be flexed to allow its groove 11 to displace rib 10 therefrom or the cover should be flexed to flex rib 10 out of groove 11. The easiest and most suitable action for the size and shape of container shown in Fig. 1 is illustrated in Fig. 4 where it is shown that the overhanging cover edge flange 19 may be gently pressed at, say, two points to cause the cover to bow sufficiently to flex this rib 10 and cause it to be lifted out of groove 11. Although a direct upward pull in the direction of the arrow, shown in Fig. 3, on this overhanging cover flange 19 will not release the cover, a slight downward sidewise pressure applied against the overhanging portion of flange 19 will flex flange 9 and rib 10 and cause this rib 10 to be flexed out of groove 11.

The container shown in Figs. 1 to 4, inclusive, is intended for the storage of pies, cookies, biscuits, and many other edibles, and where this storage is for freezer use and low temperatures are encountered, the material well suited for the purpose may be flexible, non-toxic and odorless plastic known generally in the trade as polyethylene. Other materials may, of course, be used as long as the present locking action between the cover and container is present or the structure disclosed herein is employed.

A different form of container employing the invention is illustrated in Figs. 5 to 8, inclusive. Instead of the container being circular as in Figs. 1 to 4, inclusive, the container in Figs. 5 to 8, inclusive, is rectangular. Body 25 is of considerable depth, relatively speaking, as when compared to the container shown in Fig. 1, and cover 26 is raised a distance above the line of separation between the body and the cover. However, cover 26 is provided with a downwardly projecting flange 27 which also has a rib 28 like rib 10 on flange 9. Body 25 is furnished with a groove 29 into which rib 28 fits in a vapor-tight sealing relation. It will be observed that the thickness of vertical wall 30 of body 25 may be increased slightly and may have a horizontal ledge or flange 31 extending outwardly therefrom.

Cover 26 is also provided with a similar ledge or flange 32 so that the flat faces of these flanges may lie tightly against each other when rib 28 is in groove 29. The raised portion 34 of the cover is increased in thickness at flange 32. It will be observed that there is considerable distance between opposing side walls of both the body 25 and the cover 26. The arrangement of flange 27 and rib 28 locking in groove 29, together with flanges 31 and 32 abutting each other at the line of separation, very uniquely keeps the cover 26 in position upon body 25 and provides a tight closure that effects a vapor-tight seal.

If the cover 26 is the part made of flexible material, such as polyethylene or the like, Fig. 6 illustrates how the cover 26 may be easily removed by applying pressure inwardly against the sides near one of the ends of the container. If the body part is made of flexible material instead, the same action would free the body from the cover. It is understood, of course, that it is desirable to make both parts of polyethylene because this material is particularly suitable for use in food containers, although its flexibility increases the difficulty of providing a suitable closure means. However, the closure means disclosed herein is primarily intended for an all-polyethylene container, but I do not intend to be limited thereto as long as the closure means disclosed is employed.

Again, I wish to point out that the distance *c* between the upper edge of rib 28 and the under face of cover flange 32 is substantially equal to the distance *d* between the upper face of groove 29 and the upper face of body flange 31. This arrangement likewise causes the rib 28 to be held tightly in groove 29 against its upper face and further causes the two flanges 31 and 32 to be pulled and held tightly together. This also tends to add

to the rigidity of the cover and body structure along the line of closure and to keep the cover 26 in position on body 25.

It will be understood that a reversal of the parts between the body and the cover will produce substantially the same results and to this extent it is intended that this reversal of parts is to come within the scope of the invention herein disclosed.

Without further elaboration, the foregoing will so fully explain the character of my invention that others may, by applying current knowledge, readily adapt the same for use under varying conditions of service, without eliminating certain features, which may properly be said to constitute the essential items of novelty involved, 15 which items are intended to be defined and secured to me by the following claims.

I claim:

1. A flexible plastic container and cover therefor, said container and said cover having such local flexibility relative to each other that the contour of either at a local portion may be changed relative to the other by the flexing of either or both of said parts, a peripheral flange on said cover seated upon an abutting face on said container when said cover is in position to close said container, and means to lock said cover in closed position on said container against displacement by an outward pull or force against said cover, said means being releasable to free said cover by a relative flexing movement changing the contour locally of one of said parts, said means including a laterally extending substantially continuous rib on said cover and a substantially continuous groove in said container to receive said rib, the distance between the upper edge of said groove and said abutting face on said container bearing a direct relation with the distance between said rib and said peripheral flange on said cover.

2. A container having a base with upstanding side wall structure and a peripheral top face, and a cover of relatively flexible plastic material provided with an edge flange resting upon said top face of said upstanding side wall structure and projecting therebeyond and removable from the container by pressure being applied to said projecting edge flange without appreciable distortion of said upstanding side wall structure, and means to lock said cover in position and provide a tight fit and a vapor tight seal comprising a depending flange on said cover spaced inwardly from said projecting edge flange and extending into said container, a laterally extending substantially continuous rib on said depending flange, there being a substantially continuous groove in said upstanding side wall structure to receive said rib, said groove being spaced from the top edge of said side wall structure a distance to hold said cover tightly upon the said top face of said side wall structure against displacement by an upward pull when said rib is in said groove, the flexing of said projecting edge flange of said cover freeing said cover by dislodging said rib from said groove without appreciable distortion of said side wall structure.

3. A container having a base and upstanding side wall structure with a peripheral top face and of relatively flexible plastic material, a cover provided with an edge flange resting upon said top face of said upstanding side wall structure, and means to lock said cover in position and provide a tight fit comprising a depending flange on said cover spaced inwardly from said edge flange and extending into said container, a laterally extending substantially continuous rib on said depending flange, there being a substantially continuous groove in said upstanding side wall structure to receive said rib, said groove being spaced from the top edge of said side wall structure a distance to hold said cover tightly upon the said top face of said side wall structure against displacement by an upward pull on the cover when said rib is in said groove, said rib being releasable from said groove to free said

cover by a flexing of a local portion of said side wall structure without appreciable distortion of said container.

4. A container having a base and upstanding side wall structure with a peripheral top face and of relatively flexible plastic material, a cover provided with an edge flange resting upon said top face of said upstanding side wall structure, and means to lock said cover in position against displacement by an upward pull thereon and provide a tight fit comprising a depending flange on said cover spaced inwardly from said edge flange and extending into said container, a substantially continuous laterally extending rib on said depending flange, there being a substantially continuous groove in said upstanding side wall structure to receive said rib to hold said cover tightly upon said top face of said side walls against an upward pull applied to said edge flange of said cover when said rib is in said groove, said rib being releasable from said groove to free said cover by a flexing of a local portion

of said side wall structure without appreciable distortion of said container.
